(57) **CLAIM**

I claim the ornamental design for a trial shell, as shown and described.

DESCRIPTION

FIG. 1: is a perspective view of the trial shell showing the new, original and ornamental design;

FIG. 2: is a front view thereof;

FIG. 3: is a first side view thereof;

FIG. 4: is a back view thereof;

FIG. 5: is a second side view thereof;

FIG. 6: is a top view thereof; and

FIG. 7: is a bottom view thereof.

FIG. 8: is a perspective view of the trial shell showing the new, original and ornamental design of a second embodiment;

FIG. 9: is a front view thereof;

FIG. 10: is a first side view thereof;

FIG. 11: is a back view thereof;

FIG. 12: is a second side view thereof;

FIG. 13: is a top view thereof;

FIG. 14: is a bottom view thereof;

FIG. 15: is a perspective view of the trial shell showing the new, original and ornamental design of a third embodiment;

FIG. 16: is a front view thereof;

FIG. 17: is a first side view thereof;

FIG. 18: is a back view thereof;

FIG. 19: is a second side view thereof;

FIG. 20: is a top view thereof; and,

FIG. 21: is a bottom view thereof.

The features shown in broken lines in various Figures are for illustrating reference or environmental structure.

1 Claim, 15 Drawing Sheets
